UNITED STATES PATENT OFFICE

CHARLES WINKLER, OF NEW YORK, N. Y.

FOUR-IN-HAND NECKTIE

Application filed June 24, 1931, Serial No. 546,587. Renewed December 1, 1931.

This invention relates to neckwear and particularly to an improved four-in-hand necktie, the object being to provide a high class pleasing appearing tie which will properly slip back and forth as it is slid around the collar and which will present a proper knot when tied.

Another object of the invention is to provide a four-in-hand necktie wherein the form 10 of stitching will be arranged in two or more rows at the point where the knot is to be formed, the stitching being so arranged as to connect the lining of the tie to the back part of the tie body.

15 A further object of the invention is to provide a four-in-hand tie which may have the general shape of ties on the market but which is formed from a blank with the edges turned in and then connected by a spaced zigzag line 20 of stitching connecting the curved edges of the turned-in portions together in abutting relation.

A still further object of the invention is to provide an improved tie of the four-in-hand type which produces a flat seam designed to give a finish to the tie and also give an efficient knot forming and sliding structure.

In the accompanying drawing—

30 Figure 1 is a blank of a tie and a lining disclosing certain features of the invention.

Figure 2 is an enlarged transverse sectional view through Figure 1 on line 2—2.

Figure 3 is a rear view of the complete tie 35 ready for use.

Figure 4 is an enlarged view showing part of the tie adjacent the knot-forming portion.

Figure 5 is a sectional view through Figure 4 on line 5—5, the same being on an enlarged scale.

Figure 6 is a sectional view through Figure 4 on line 6—6, the same being on an enlarged scale.

45 Heretofore, neckties of the four-in-hand type have been formed so that one edge at the back will overlap the other, thus giving an extra thickness which naturally produces a ridge. In the present invention, the structure has been designed to overcome this ob-

jection and produce a tie having a smooth surface, and giving a more resilient action at the point of forming a knot. In addition, the smoothness or rather evenness throughout the tie presents an easier sliding structure for sliding round the collar as there are no extra thicknesses to overcome.

In forming a tie embodying the invention, a blank 1 is provided, the same being cut from a desired material and of a desired size; 55 preferably the ends 2 and 3 are hemmed to present a pleasing appearance while the sides 4 and 5 are turned inwardly as illustrated particularly in Figure 2 so that there will be rounded edges 6 and 7 which are adapted 60 to abut when the tie has been completed as shown in Figures 3 and 6. After the tie has been formed as shown in Figure 1, it is folded so that the side edges 4 and 5 will be folded over the lining 8 so that the rounded edges 6 and 7 will abut. In order to connect these abutting edges, a special line of stitching 9 is provided which preferably starts from point 10 and extends substantially to point 11 along the respective abutting edges 6 and 7. This line of stitching 65 passes through the lining to the opposite abutting edge and finally through the lining again, after which the needle placing the thread is moved in a direction substantially 70 parallel with the abutting edge and caused to again pass through the lining and one of the abutting edges in an upward direction so that the section of stitches connecting the abutting edges will be at spaced intervals, 75 as for instance, one-eighth of an inch, one-quarter of an inch or half an inch apart.

As illustrated in Figure 4, the portion 12 of stitching 9 forms a connection portion for connecting the abutting edges together and 80 the portion 13 forms the forwardly extending portion which merges into the next connecting portion 12. This produces a zigzag line of stitching as illustrated in Figure 4. As illustrated in Figure 5, the respective stitches extend through the lining 8 so as to hold the same in place and also to present a good base for carrying the stitches. As illustrated in 85 Figure 4, the stitching which extends from point 10 leaves the abutting edges 6 and 7 100

at point 14 and a few stitches extend substantially at right angles to the edges 6 and 7, after which a row of stitches 15 is provided, said stitches 15 extending through the rear or back of the necktie body and through the lining 8 as shown in Figure 5. The line of stitching 15 extends to point 16 and then merges into line of stitching 17 which extends to point 18, and at 18 the line of stitching 10 merges into another line of stitching 19 which is parallel to the stitching 15. The line of stitching 19 turns at 20 so that the section 21 is near the abutting edges 6 and 7, after which the line of stitching returns to its regular 15 formation and position for connecting the abutting edges together. It will be noted that the lines of stitching 15 and 19 are parallel and are near the edges of the back of the body of the necktie. The lines of stitching 20 15 and 19 may be of any desired length but are preferably of a length to occupy the usual space or portion of the tie utilized to make the knot when the tie is in use. This arrangement of stitching at this place holds 25 the lining firmly in place and parallel with the front and rear parts of the body of the tie, so that there is less tendency to wrinkle or pinch the body of the tie at the point of knotting by reason of the fact that the edges 30 of the lining are stitched to the back of the body.

In placing the various lines of stitching in place, the body of the tie is substantially in the position shown in Figure 3 and the body 35 is never reversed. It will thus be seen that the body of the tie is first formed as shown in Figure 1 and the lining applied, after which the side portions of the blank are bent over to the position shown in Figure 3 and 40 then the various lines of stitching applied as just described. By this method of forming a tie, it is unnecessary to reverse or turn inside out the tie which is done with many ties now on the market.

45 As indicated in Figure 3, an indicating structure 22 is provided for indicating the correct position of the necktie in regard to the collar when first applying the tie. This indicating means may be a line of buttonhole 50 stitching or in fact stitching of any kind. Preferably the stitching is some kind which projects outwardly a short distance so that it may be readily felt by the fingers. When the necktie is placed around the collar the same 55 is slid back and forth until the member 22 is at one end of the collar. The tie is then tied in the usual manner and by reason of the location of the tie as just described, both ends 60 of the tie will be of substantially the same length.

I claim:

1. A four-in-hand tie comprising a body, having edges folded inwardly and lying flat against the rear face of the body, a lining 65 positioned between the front and rear faces

of the body, and a line of stitching extending through the abutting edges of said turned-in portions and through said lining for connecting the lining to the rear of the body of the tie and for connecting said edges together. 70

2. A four-in-hand tie comprising a body folded to present a tube with the adjacent edges of the folded parts turned-in, said edges being rounded, a lining arranged within 75 said tube and extending from one side to the other thereof, a line of stitching extending through said rounded edges and through said lining, said stitching extending substantially from one end of the tie to the other and at the portion forming the knot 80 forming three parallel rows of stitching extending through the back of the tie and through the lining.

3. A method of forming a four-in-hand 85 tie consisting in cutting a blank out of sheet textile fabric, turning the edges inwardly for forming flanges, said flanges lying flatwise against the body of the tie, folding the side portions of the tie so that the rounded 90 parts at the juncture of the flanges and the tie will abut, placing a lining within the tie body and securing said abutting edges together and to said lining by applying a line 95 of stitching to said abutting edges and the lining.

4. A four-in-hand tie comprising a body folded to present a tube, a lining arranged within said tube and extending substantially 100 from one end to the other and also from one side thereof to the other, and a plurality of rows of stitching at the knot-forming part of the tie only and positioned to extend only through the back of the tie and through said lining, said rows of stitching comprising a 105 central row of stitching connecting the edges of said folded body together, a side row of stitches on each edge of said body extending through the back of the body and through said lining and substantially transversely 110 positioned rows of stitching extending substantially from one side of the body to the other, said transversely positioned rows of stitching extending through the back of said body and said lining. 115

5. A four-in-hand necktie comprising a body folded to present a tube with adjacent edges of the folded parts turned in, a lining arranged within said tube and extending substantially from one side to the other thereof and substantially from one end of the body to the other and stitching for connecting said lining to the back of said body, said stitching extending substantially from one 120 end of said body along said turned-in edges for connecting said edges together from one end of the body to the knot-forming part of the tie, then laterally to one edge of said body, along said edge for substantially the 125 length of the knot-forming part of the tie, 130

substantially transversely of the tie to the opposite edge of said body, along said opposite edge back to the beginning of the knot-forming part of the tie, transversely to said 5 inturned edges and then along said inturned edges to the opposite end of the tie, said stitching at all points extending through only the back of said body and through said lining.
